UNITED STATES PATENT OFFICE.

MARC SOLON, OF TRENTON, NEW JERSEY.

DESIGN FOR A BAFFLE BRICK.

Application filed September 23, 1926. Serial No. 19,147. Term of patent 7 years.

To all whom it may concern:

Be it known that I, MARC SOLON, a subject of the King of Great Britain, and resident of Trenton, in the county of Mercer and State of New Jersey, have invented a new, original, and ornamental Design for a Baffle Brick, of which the following is a specification, reference being had to the accompanying drawing, in which—

Fig. 1 is a front elevation of a baffle brick exhibiting my new design; Fig. 2 a side elevation thereof; Fig. 3 a bottom view and Fig. 4 a top view.

I claim:

The ornamental design for a baffle brick, as shown.
